(57) **CLAIM**

The ornamental design of a handheld dual container as shown and described.

DESCRIPTION

FIG. 1 is an upper perspective view of a dual handheld container showing our new design;

FIG. 2 is a front side view thereof;

FIG. 3 is a rear side view thereof;

FIG. 4 is a left side view thereof;

FIG. 5 is a right side view thereof;

FIG. 6 is a top view thereof;

FIG. 7 is a bottom view thereof;

FIG. 8 is a lower perspective view thereof;

FIG. 9 is an upper perspective exploded view thereof; and, FIG. 10 is an upper perspective exploded view thereof.

Any shading is not a feature of the design but is utilized to illustrate the surface contours of the handheld dual container in the drawings.

1 Claim, 10 Drawing Sheets
